UNITED STATES PATENT OFFICE.

FRANCIS MARION STACKPOLE, OF WORTHINGTON, WEST VIRGINIA.

ANTISPREADING DEVICE FOR RAILS.

1,129,750.

Specification of Letters Patent. Patented Feb. 23, 1915.

Application filed June 17, 1914. Serial No. 845,687.

To all whom it may concern:

Be it known that I, FRANCIS MARION STACKPOLE, a citizen of the United States, residing at Worthington, in the county of Marion and State of West Virginia, have invented certain new and useful Improvements in Antispreading Devices for Rails, of which the following is a specification.

This invention relates to anti-spreading devices for rails, one of the objects being to provide a compact structure, capable of expeditious application to the rails for preventing lateral thrust, which is very frequently occasioned especially in rounding sharp curves.

Another object resides in the provision of a device capable of manual attachment by which the opposite sides of the rail may be braced if so desired, an actuating member being connected to the structure, so as to simultaneously engage the outer rail engaging sections; a lever being operated on a vertical axis, so as to provide a relatively flat device between the track rails preventing interference with any of the train trips, since it is well known that levers, etc., very often depend from the train for contact with an abutment or the like on the track for giving a signal, opening the train pipe or the like, and it is to eliminate this undue interference that the present formation is devised.

Other objects as well as the nature, characteristic features and scope of my invention will be more readily understood from the following description taken in connection with the accompanying drawings and pointed out in the claims forming a part of this specification.

Referring to the drawings: Figure 1 is a side elevation of an anti-spreading device constructed in accordance with my invention, illustrating the application thereof, Fig. 2 is a top plan view, showing the rails removed, and Fig. 3 is a similar view, showing the sections disengaged from the rails and separated, illustrating the manner in which the actuating lever is associated therewith, Fig. 4 is a side elevation of a modified form of anti-spreading device, illustrating the application thereof, Fig. 5 is a top plan view of the device, showing the rails removed therefrom, and Fig. 6 is a similar view, the outer and inner rail-engaging sec-

tions being separated and the actuating lever associated therewith.

In the drawings, wherein is illustrated the preferred embodiment of this invention in order to illustrate the application thereof, a pair of rails 5 are provided which in the present instance are of the usual configuration, said rails being in connection with my improved anti-spreading device, the latter being generally designated at 6 and comprises in the present instance a pair of sections 7 and 8, each of which comprises a metallic strap, the outer ends of which are engaged beneath the base flanges of the rails, having the free terminals thereof engaged with the top of the base flanges and the webs of the rails and then bent outwardly into parallelism with the webs as indicated at 9, so as to reinforce the ends. The section 8 has its inner end arranged subjacent the inner end of the section 7, said section 8 being off-set as indicated at 10, so that said inner end thereof will lie in spaced relation to the inner end of the section 7, to accommodate the actuating lever therebetween, the latter likewise comprising a metallic strap, one end of which is pivotally engaged with the section 7, as indicated at 12 and shown to advantage in Fig. 3, said lever being pivoted, at 13, to the section 8, so as to simultaneously actuate the sections 8 when pressure is exerted upon said lever, the free end 14 of the latter being off-set, so as to lie below the plane of the operating lever, thereby providing ample space between the section 7 and said operating end of the actuating lever to permit of the engagement of the hand therewith by which the sections are disengaged from the rails. After the sections 7 and 8 have been engaged with the rail 5 by the actuation of the lever 11, in order to prevent their accidental displacement by the vibration due to the rolling stock passing over the rails, or the like, openings 15 are provided in the sections 7 bersome nature, for instance, as ties upon to aline when the sections are clamped into engagement with the rails, and are adapted for engagement with a pin or locking element 16, the latter being provided with a head which fits in a complementary recess in the section 7, as indicated in Fig. 3, in order to prevent the projecting of the pin 16, upwardly beyond the plane of the section 7.

In operation, assuming that the rails 5 have been engaged with their respective sections 7 and 8, and it is desired to clamp said sections thereon, pressure is exerted on the lever 11, until the latter is arranged subjacent the section 7 after which the locking element 16 is then engaged through the alined openings 15 of the sections and the lever, so as to positively prevent the accidental displacement of the sections. Should it be desired to disengage the sections 7 and 8 from the rails, pin 16 is removed and pressure is exerted on the operating end 14 of the lever 11, so as to cause the lateral movement of the sections in view of the manner in which they are pivotally connected with the lever.

In Figs. 4, 5 and 6 of the drawings, a similar formation is provided for, rails 5' being shown in Fig. 4 in order to illustrate the application of this form. The device shown in these figures comprises sections 7' and 8' identical in configuration to the sections 7 and 8, as shown in Figs. 1, 2 and 3, said sections having a lever 11' engaged therewith which is identical with the lever 11 in the original form and is actuated in the same manner so as to engage the sections 7' and 8' with the rails 5'. However, in conjunction with the sections 7' and 8' and the lever 11', is a rail engaging intermediate section 17, the opposite ends 18 of which are bent into engagement with the upper faces of the base flanges of the rail 5' and into engagement with the inner faces of the webs of said rails so as to prevent either inward or outward lateral movement of the rails should undue pressure be exerted thereon by the rolling stock passing over the rails. The intermediate rail-engaging section 17 comprises a single metallic strap and is pivoted approximately midway its ends with the section 7', as indicated at 19 and shown to advantage in Fig. 6, in order to permit of the ready disengagement and engagement of the member from the rails. In order to secure the sections 7', 8' and 17 from displacement, an opening 20 is formed in said section 17, which alines with openings 15' in the sections 7' and 8' and in the lever 11', said opening 20 being counter-sunk for engagement with the head of the pin or securing element 21 which is engaged through the opening 20 in the section 17 and the openings 15' in the sections 7' and 8' and the lever 11'. In the operation of this form as shown in Figs. 4, 5 and 6, assuming that the rails 5' are engaged with their respective sections 7' and 8', the ends 18 of the section 17 are engaged with the inner faces of the rails and pressure exerted on the lever 11', so as to cause the simultaneous actuation of the sections 7' and 8' into engagement with the outer faces 65 of the rail, thereby bracing the rails, both

at their outer and inner sides, so as to positively prevent accidental displacement.

Although in the present instance, these devices have been described as anti-spreading or anti-creepers for rails, it is nevertheless to be understood that these may take the place of ties on railroads in places where the rolling stock is not of such cumbersome nature, for instance, as ties upon which tracks are mounted over which only coal cars which convey the coal from a coal mine to a transportation receptacle or the like, is used, it being well known that these cars are of a very small configuration, so as not to necessitate such an enlarged or cumbersome securing base for the rails upon which they travel.

It will be understood that the above description and accompanying drawings comprehend only the general and preferred embodiment of my invention and that various minor changes in details of construction, proportion and arrangement of parts may be made within the scope of the appended claims and without sacrificing any of the advantages of my invention.

Having thus fully described my invention what I claim as new and desire to secure by Letters Patent is:

1. An anti-spreading device for rails including rail-engaging sections, and means for actuating said sections into engagement with the rails and operable on a vertical axis to provide a relatively flat structure between the rails.

2. An anti-spreading device for rails including a pair of relatively movable sections, a lever for actuating said sections, said lever being in pivotal engagement with each of said sections so as to simultaneously actuate the latter when pressure is exerted on said lever, and means for engagement through said sections and through said lever for securing the sections against accidental displacement from the rails.

3. An anti-creep for rails including a pair of relatively movable sections for engagement with the rails, an actuating lever in pivotal engagement with said sections for simultaneously actuating said sections into engagement with said rail and simultaneously releasing said sections from said rail, at times, and a securing pin adapted for engagement through said sections and said lever for securing said sections against accidental displacement.

4. An anti-creep for rails including a pair of relatively movable sections, one end of each of which is in engagement with the base flange and the outer face of the web of one of the rails, the inner ends of said sections overlying each other, one of said ends lying in spaced-apart relation to the opposite end, a lever mounted between said inner ends and being pivotally engaged with both

of said sections for simultaneously actuating the same for engagement with or disengagement from the rails, said lever having its free end off-set to provide a handle portion 5 to facilitate the operation of the lever, and a locking pin for engagement through said sections and said lever for retaining the same together from accidental displacement.

5. An anti-creeper for rails including a 10 pair of sections for engagement with the outer faces of the rails, a lever for actuating said sections, and a section pivotally engaged with one of said first mentioned sections for engagement with the inner faces of 15 the rails.

6. An anti-creeper for rails in combination with a pair of parallel rails, including a pair of relatively movable sections for engagement with the outer faces of said rails, 20 a lever for simultaneously actuating said sections into engagement with and out of engagement from the rails, and an intermediate section pivoted approximately midway its ends to one of said sections, the opposite ends thereof being turned into angled 25 relation to the body for engagement with the

inner faces of said parallel rails to prevent lateral thrust either inwardly or outwardly of the rails.

7. An anti-creeper for rails in combination with a pair of parallel rails, including a pair of relatively movable sections, an actuating lever in pivotal engagement with said sections for simultaneously actuating the latter into engagement with or out of engagement with the rails, an intermediate section pivotally engaged with one of said first mentioned sections, having the opposite ends thereof turned in angled relation to the body for engagement with the inner faces of said parallel rails, and means for engagement through said intermediate section, said relatively movable sections and said lever whereby accidental displacement of any of the sections is prevented. 30 35 40 45

In testimony whereof I affix my signature in presence of two witnesses.
